UNITED STATES PATENT OFFICE.

FRANK W. LOWE, OF BOSTON, MASSACHUSETTS.

PICTURE-FRAME.

SPECIFICATION forming part of Letters Patent No. 377,567, dated February 7, 1888.

Application filed February 14, 1887. Serial No. 227,589. (No model.)

To all whom it may concern:

Be it known that I, FRANK W. LOWE, a citizen of the United States, residing at Boston, in the county of Suffolk and State of Massachusetts, have invented a new and useful Improvement in Frames for Pictures, Slates, and such like Articles, of which the following is a specification.

The object of this invention is to provide a frame for pictures, slates, and such articles which combines simplicity of construction, facility of application, and protection for the edge of the picture or other article placed therein.

15 Figure 1 of the accompanying drawings is a front elevation of this improved picture-frame. Fig. 2 represents a serpentine wire blank, which constitutes, when folded longitudinally, a segment of this improved picture-frame. 20 Fig. 3 represents transverse sections in different forms of the body of this improved picture-frame. Fig. 4 represents a segment of this improved picture-frame constructed of wire having a fibrous or elastic coating.

25 Similar letters of reference indicate corresponding parts in the different figures.

This improved picture-frame A comprises a series of U-shaped loops, *a*, composed of a continuous wire. These U-shaped loops are 30 arranged adjacent to one another and form a continuous groove, *b*, on the inside of the frame, in which the edge of the picture is inserted. Each loop comprises an arm, 1, on the front side of the frame and an arm, 2, on 35 the rear side thereof, connected by an arch, 3, at the outer edge of the frame. The front arm of each of the loops is integrally connected at its inner end by the curved wire 3 with the front arm of the adjacent loops, and 40 the rear arm of the same loop is integrally connected at the rear of the frame by a corresponding curved portion of the wire with the rear arm of the adjacent loop.

The loops may be either square or rounded 45 at their outer ends, as shown in Fig. 3. The meeting ends of the wire are preferably twisted together and into the form of an eye, *c*, at the center of the upper end of the frame, which eye serves for hanging the picture.

50 In frames for slates the eye *c* will be omitted, and the ends of the wire will be brought together and secured by any suitable clasp or fastening device.

The wire of which the frame is composed 55 may be provided with a fibrous or elastic coat-

ing, *d*, if desired, as shown in Fig. 4, so that the frame will be comparatively noiseless. The coated wire is preferably used in frames for slates.

The corners of the frame are preferably 60 rounded, as shown in Fig. 1. In forming these frames a piece of wire is first bent into a serpentine blank, as shown in Fig. 2. This blank is then bent or folded longitudinally into U shape, as shown in Fig. 3. 65

In placing the picture in the frame the latter will be stretched or expanded both longitudinally and laterally for the admission of the picture, and then compressed, so that the edge of the picture rests in the continuous 70 groove formed by the contiguous or adjacent U-shaped loops. In case the frame is made of wire which is comparatively rigid the picture may be bent for insertion in the frame; or the ends of the wire composing the frame 75 may be untwisted, the frame opened, the picture inserted, the frame closed thereon, and the ends of the wire retwisted or connected.

I claim as my invention—

1. A picture-frame consisting of a series of 80 adjacent U-shaped loops forming a continuous groove on the inside of the frame for the reception of the picture, said loops being composed of a continuous wire, the arms of each loop being integral with the adjoining arms of adjacent loops, substantially as described.

2. A picture-frame consisting of a series of adjacent U-shaped loops forming a continuous groove on the inside of the frame for the reception of the picture, said loops being 90 composed of a continuous wire, the arms of each loop being integral with the adjoining arms of adjacent loops, the ends of the continuous wire being coiled into an eye at the top of the frame, substantially as described. 95

3. A picture-frame consisting of a series of adjacent U-shaped loops forming a continuous groove on the inside of the frame for the reception of the picture, said loops being composed of a continuous coated wire, the arms of 100 each loop being integral with the adjoining arms of adjacent loops, substantially as described.

In testimony whereof I have signed my name to this specification in the presence of two subscribing witnesses.

FRANK W. LOWE.
